CLEMMA R. RANEY, OF CHICAGO, AND BERT R. BENJAMIN, OF OAK PARK, ILLINOIS,
ASSIGNORS TO INTERNATIONAL HARVESTER COMPANY OF NEW JERSEY, A COR-
PORATION OF NEW JERSEY.

CORD-HOLDER FOR GRAIN-BINDERS.

1,272,711.

Specification of Letters Patent.

Patented July 16, 1918.

Application filed January 31, 1916. Serial No. 75,362.

To all whom it may concern:

Be it known that we, CLEMMA R. RANEY and BERT R. BENJAMIN, citizens of the United States, and residents, respectively, 5 of Chicago, in the county of Cook and State of Illinois, and of Oak Park, in the county of Cook and State of Illinois, have invented certain new and useful Improvements in Cord-Holders for Grain-Binders, of which 10 the following is a full, clear, and exact specification.

Our invention relates to cord holders for grain binders.

In the operation of cord holders of the 15 type described in the Benjamin Patent, No. 865,754, issued September 10, 1907, it has been found that an operator not familiar with the operation of the mechanism will more or less frequently, in an initial thread- 20 ing of the device, draw the cord from the needle through the slot in the breast plate and into the cord receiving groove of the rotatable cord holding disk, and will hold the end of the cord at a distance from the 25 cord holding mechanism, and when the needle is brought upward and outward, it delivers another strand of cord to the holder and the knotting and holding mechanism, moving in unison, will carry the cords be- 30 tween the disk and cord holder plate while the knot is being tied and the two strands of cord severed by the knife. The knot is then stripped from the knotter hook and the machine is presumed to be in proper condition for further continuous operation, but 35 one end of the length of cord held by the operator is still drawn between the disk and plate and will be carried around the disk shaft instead of being discharged, the result 40 being that the plate and disk are separated to an extent that they will not perform their proper function of holding the cord.

Our improvement has for its object to provide an improved construction wherein 45 even although the cord is improperly placed in the cord holder initially and the loose extra end of twine is left in the holder, the mechanism will operate efficiently and without any disorganization thereof due to 50 the presence of the cord.

We obtain these objects by an improved construction of the cord holder plate carrying improved means whereby the cord that was in the hand of the operator is prevented

from passing around the disk shaft between 55 the plate and the disk and will be discharged from the mechanism.

In the accompanying drawings we have illustrated one embodiment which our invention may assume in practice, showing the 60 same in connection with a cord holder of the type described and claimed in the above mentioned patent.

In these drawings:

Figure 1 is a sectional plan view of the 65 cord holding mechanism, showing the same improperly threaded and when the parts are beginning the knotting operation.

Fig. 2 is a view similar to Fig. 1, showing the result of improper threading, and also 70 our improved means which prevents the entry of the piece of cord between the plate and disk.

Fig. 3 is a top plan view of our improved 75 cord holder plate.

Fig. 4 is a side elevation of Fig. 3.

Fig. 5 is a side elevation of the disk and plate, partly in section, and illustrating their coöperation.

The mechanism shown in these drawings 80 includes a breast plate 1, on which is mounted the usual rotatable knotter hook 2, rotatable cord holder disk 3, stationary cord holder plate 4, and fixed knife 5, these parts being of the construction described in the 85 Benjamin patent mentioned above. As in that construction, the disk 3 rotates upon the cord holder plate 4 and is provided with parallel oppositely extending cord receiving notches 7 and 8 on its opposite sides communicating with cut-away portions 9 and 10, shoulders 11 and 12 being provided thereon adapted to engage with the twine in the manner described therein. The cord holder plate is also provided with an upstanding 90 annular wall 13 having a cord-receiving notch 14 at one end thereof and a depression 15 at a point adjacent the knotter hook, as well as a raised cord engaging portion 16 coöoperating with the bottom of the disk to 100 hold the twine. As in the construction described in that patent, the plate 4 is also provided with a side cut-away, as shown at 17, and relieved, as shown at 18, to permit the cord to be withdrawn by the needle. In 105 our improved construction a lug 19 is extended from the plate 4 at a point adjacent the pivot 20 of the disk, this lug preferably

being of the same height as the raised portion 16 and provided with a vertical side wall 21 projecting outward beyond the cut-away portion 17 and a vertical end wall 22 disposed at an angle of slightly over 90° to the wall 21, the other side wall 23 being inclined to wall 22, as shown, and extending backward therefrom to a point over the axis of the disk.

10 In the operation of our improved construction, it has been found that when the knotter is threaded, as shown in Fig. 1, the length of cord held by the operator and severed by the knife as the disk is rotated, strikes the lug 19 and is held thereby as the disk rotates in such a manner that it can not pass between the disk and the plate and must subsequently be discharged from the plate, being fed out between the disk and plate 15 and dropped out through the cut-away portion 17. It will be noted that in our improved construction it makes no difference whether the knotter is properly or improperly threaded, our improved means acting to prevent any interference of the efficient operation of the knotter when the latter is improperly threaded, thereby enabling the device to be used by even the most unskilled operators without any difficulty being 20 experienced. Thus from the farmer's standpoint time is saved, and from the manufacturer's standpoint the time and money incurred in furnishing experts to correct the difficulties resulting from improper manipulation by the operator have also been saved. Obviously, the construction shown is also 25 exceedingly simple and adapted to be applied to a cord holder of the construction described at practically no expense.

30 While we have in this application specifically described one embodiment which our invention may assume in practice, it is, of course, to be understood that the construction may be modified without departing 35 from the spirit of the invention, and that it is our intention to include all such modifica-

tions within the scope of the appended claims.

What we claim as our invention and desire to secure by Letters Patent is:

1. In a cord holder for binders, a rotatable cord holder disk, a knife for severing cord carried around thereby, and a cord holder plate on which said disk is rotatable having a laterally extending sharp edged portion disposed adjacent the pivot of said disk and within the path of a length of cord severed by said knife. 55

2. In a cord holder for binders, a rotatable cord holder disk, a knife for severing cord carried around thereby, and a cord holder plate on which said disk is rotatable having a square cornered laterally extending portion disposed adjacent the axis of said disk and disposed within the path of a length of 60 waste cord severed by said knife.

3. A cord holder plate having a raised cord engaging surface thereon and a cut-away portion at one of its edges, said cord holder plate having a laterally extending lug 70 of substantially the height of said raised portion extending therefrom at a point intermediate the ends of said cut-away portion.

4. A cord holder plate having a raised cord engaging surface thereon, and a cut-away portion at one of its edges extending vertically with respect to the plate, said cord holder plate having a laterally extending lug of substantially the height of said 80 raised portion extending therefrom at a point intermediate the ends of said cut-away portion, said laterally extending lug having sharp edges extending at right angles to the surface of the plate. 85

In testimony whereof we affix our signatures, in the presence of two witnesses.

CLEMMA R. RANEY.
BERT R. BENJAMIN.
